US00D928745S

(12) **United States Design Patent** (10) **Patent No.:** **US D928,745 S**
(45) **Date of Patent:** **** Aug. 24, 2021**

(54) **EARBUD**(71) Applicant: **Apple Inc.**, Cupertino, CA (US)(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Sung-Ho Tan**, San Francisco, CA (US); **Clement Tissandier**, San Francisco, CA (US); **Eugene Antony Whang**, San Francisco, CA (US); **Rico Zörkendörfer**, San Francisco, CA (US)(73) Assignee: **Apple Inc.**, Cupertino, CA (US)(***) Term: **15 Years**(21) Appl. No.: **29/764,724**(22) Filed: **Dec. 31, 2020****Related U.S. Application Data**

(63) Continuation of application No. 29/741,273, filed on Jul. 10, 2020, now Pat. No. Des. 907,010, which is a continuation of application No. 29/705,727, filed on Sep. 13, 2019, now Pat. No. Des. 906,297.

CLAIM

The ornamental design for an earbud, as shown and described.

DESCRIPTION

FIG. 1 is a front perspective view of an earbud showing the claimed design;

FIG. 2 is a rear perspective view thereof;

FIG. 3 is a side perspective view thereof;

FIG. 4 is another rear perspective view thereof;

FIG. 5 is another side perspective view thereof;

FIG. 6 is another rear perspective view thereof;

FIG. 7 is a side view thereof; and,

FIG. 8 is another side view thereof.

FIG. 1

FIG. 2

FIG. 3

FIG. 4

FIG. 5

FIG. 6

FIG. 7

FIG. 8
